BUILDING CONSTRUCTION

Filed April 23, 1934

FIG. 1

UNITED STATES PATENT OFFICE

2,029,009

BUILDING CONSTRUCTION

Harold E. Anning, Evanston, Ill., assignor to
 United States Gypsum Company, Chicago, Ill.,
 a corporation of Illinois

Application April 23, 1934, Serial No. 721,861

9 Claims. (Cl. 72—68)

This invention relates to building constructions, and has reference more specifically to slab constructions suitable for use as ceilings, but also being adapted for use in walls and floors.

5 In the construction of ceilings of cementitious slabs, such as slabs made of gypsum, concrete, etc., it is desirable to provide a construction which is reinforced internally and along the longitudinal edges of the slabs so as to resist any cold flow and deflection of the gypsum slabs, and also to prevent rupture of the slabs due to stresses resulting from applied loads. It is also desirable to provide a fireproof ceiling construction which may be easily erected with the slabs securely locked together.

10 An object of this invention therefore, is to provide a slab building construction which may be easily and quickly erected with a minimum of labor.

20 Another object of the invention is to provide a fireproof slab ceiling construction which is properly reinforced to withstand loads and also cold flow of gypsum; also to improve building constructions in other respects hereinafter specified and claimed.

25 Reference is to be had to the accompanying drawing forming a part of this specification, in which

Fig. 1 is a perspective sectional view of my improved ceiling construction,

Fig. 2 is a sectional elevation on an enlarged scale through the ceiling construction,

Fig. 3 is an elevation of the ceiling tiles, and

Fig. 4 is a perspective elevation of a pair of mating tiles.

30 In erecting my improved ceiling construction, I employ spaced, parallel beams 10 supported at their ends in any suitable way on the framework of a building. These beams 10 are preferably of 35 steel and in the form of I beams having webs 11, upper flanges 12 and lower flanges 13. Suspended below the beam flanges 13, I provide a plurality of cementitious slabs or tiles 14 which are preferably made of gypsum, but concrete or 40 other cementitious material may be used. The slabs 14 are preferably rectangular in shape and are provided on diagonally opposite transverse edges with outstanding cementitious tongues 15. Outstanding cementitious tongues 16 and 17 are 45 formed along diagonally opposite corners of the longitudinal edges of the slab 14.

50 One of the salient features of my invention consists in an L-shaped metallic runner 18 which is partially embedded in one of the longitudinal edges of the slab 14 at the junction of the tongue

16 with the body of the tile. The runner 18 has a horizontally extending leg 19 at the upper surface of tongue 16, and a leg 20 at the edge of the slab 14. An inwardly turned flange 21 is formed along the outer edge of the runner leg 19, said flange 21 being embedded in the tongue 16 so as to firmly attach the leg 19 to said tongue 16. A channel 22 is formed in the runner leg 19 so as to provide a shoulder 23 which is engaged by hooks 24 formed on the ends of transverse reinforcing bars 25 in the adjacent slab. A number of the bars 25, such as three in number, extend transversely through the slab 14, the centers of said bars 25 being provided with an upstanding reinforcing flange 26 to provide added stiffness to 5 10 15 said bars. The opposite ends of bars 25 are provided with hooks 26a which engage in loops 27 which are struck out from the metal of runner leg 20. The loops 27 are embedded in the slab 14 so that the runner leg 20 is firmly attached to said 20 25 30 slab 14, especially by reason of the engagement of said loops with the hooks 26a.

Longitudinal I beam reinforcing members 28 extend through the slab 14, being secured to bar flanges 26 by means of wires 29. The ends 30 of 25 members 28 are bent slightly downwardly so as to extend into the lower transverse tongue 15 and thus strengthen the same. The opposite ends of members 28 extend into the diagonally opposite transverse tongue 15 to reinforce the 30 same. A return bent flange 32 is formed on the upper edge runner leg 20 to be engaged by hooks 33 formed on the lower ends of stirrup strap hangers 34 which straddle the beams 10 and serve to connect said slabs 14 to the beams 10. If desired, the hangers 34 may have a hook end 35 which engages under the beam flange 12 to support the slabs 14. Preferably but not necessarily grout 36 may be poured into the space between the runner leg 20 and an inclined edge 37 40 45 on the slab 14 so as to provide a monolithic construction.

It will be seen that the construction described represents a ceiling structure which is easy to 50 erect and provides maximum strength to resist any ordinary loads which may be applied, and also to resist any tendency of the gypsum slabs to "cold flow". The construction can be adapted for the construction of floors, roofs or vertical walls by causing the beams 10 to extend in the proper direction.

I would state in conclusion, that while the illustrated example constitutes a practical embodiment of my invention, I do not wish to be limited 55

precisely to these details, since manifestly, the same may be considerably varied without departing from the spirit of the invention as defined in the appended claims.

5. Having thus described my invention, I claim as new and desire to secure by Letters Patent:—
1. In a ceiling construction, a plurality of supporting beams in spaced, parallel relation, a plurality of slabs of cementitious material arranged in a plane below said beams, outstanding projecting tongues formed on opposite edges and on opposed faces of each of said slabs, said tongues forming interfitting upper and lower tongues of adjacent slabs, a channel-shaped metallic runner 10 partially embedded in one edge of each tile, reinforcing bars embedded in each slab and having hook ends engaging said channel runners, and hangers engaging said channel runner and connecting said slabs to said beams.
  15. 2. In a ceiling construction, a plurality of supporting beams in spaced, parallel relation, a plurality of slabs of cementitious material arranged in a plane below said beams, outstanding tongues formed on opposite edges and on opposed faces of each of said slabs, one tongue of one slab being supported by the mating tongue of the adjacent slab, a channel-shaped metallic runner partially embedded in one edge of each tile adjacent said mating tongues, and a hanger member connected to said runners and to one of said beams so as to support said slabs.
  20. 3. In a ceiling construction, a plurality of cementitious slabs arranged in a substantially horizontal plane, outstanding tongues formed on opposite edges and on opposed faces of each of said slabs, one tongue of one slab being supported by the mating tongue of the adjacent slab, an L-shaped metallic runner partially embedded in one edge of each tile adjacent said mating tongues, one leg of said runner being interposed between said tongues, and hanger means connected to said runner for supporting a slab from a frame member.
  25. 4. In a ceiling construction, a plurality of cementitious slabs arranged in a substantially horizontal plane, outstanding tongues formed on opposite edges and on opposed faces of each of said slabs, one tongue of one slab being supported by the mating tongue of the adjacent slab, an L-shaped metallic runner partially embedded in one edge of each tile adjacent said mating tongues, a shoulder formed on said runner, a reinforcing member embedded in each slab and having a hook end engaging said runner shoulder, and

means attached to said runners for suspending said slabs from frame members.

5. In a ceiling construction, a plurality of cementitious slabs arranged in a substantially horizontal plane, outstanding tongues formed on opposite edges and on opposed faces of each of said slabs, one tongue of one slab being supported by the mating tongue of the adjacent slab, an L-shaped metallic runner partially embedded in one edge of each tile adjacent said mating tongues, a return bent flange formed on one leg of said runner, and a hanger having a hook end engaging said flange, said hanger being adapted to attach said slabs to a frame member.

6. In a ceiling construction, a plurality of cementitious slabs arranged in a substantially horizontal plane, outstanding tongues formed on opposite edges and on opposed faces of each of said slabs, one tongue of one slab being supported by the mating tongue of the adjacent slab, an L-shaped metallic runner partially embedded in one edge of each tile adjacent said mating tongues, struck out loop members formed on one leg of said runner, a reinforcing member embedded in said slab and having a hook end engaging said struck out member, and means engaging said runner for supporting said slabs on a frame member.

7. In a building slab, a rectangular cementitious slab having outstanding tongues formed on opposite longitudinal and transverse edges and on opposed faces, and an L-shaped metallic runner partially embedded in one only of said longitudinal edges, said runner extending at the surface of the angular intersection of a longitudinal tongue and said slab.

8. In a building slab, a rectangular cementitious slab having outstanding tongues formed on opposite longitudinal and transverse edges and on opposed faces, an L-shaped metallic runner partially embedded in one only of said longitudinal edges, said runner extending at the surface of the angular intersection of a longitudinal tongue and said slab, a transverse reinforcing member embedded in said slab and having one end thereof secured to said runner, a shoulder formed on said runner, and a projecting hook formed on the opposite end of said reinforcing member and adapted to engage a runner shoulder of an adjacent slab.

9. A ceiling slab as described in claim 8 characterized by a longitudinal reinforcing member embedded in said slab and secured to said transverse reinforcing member.

HAROLD E. ANNING.
